UNITED STATES PATENT OFFICE.

JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

ELECTRICAL RELAY.

1,110,430.

Specification of Letters Patent. Patented Sept. 15, 1914.

Application filed November 28, 1906. Serial No. 345,432.

To all whom it may concern:

Be it known that I, JOHN ERICKSON, a citizen of the United States of America, and resident of Chicago, Cook county, Illinois, have invented a certain new and useful Improvement in Electrical Relays, of which the following is a specification.

My invention relates to relays for controlling the circuits of electrical apparatus. 10 In relays of this character it is common to use platinum contacts, against which the relay springs are pressed in order to close the circuits. For reasons which will be well understood, it is necessary at times to clean 15 and perhaps renew these contacts. In order to facilitate such cleaning and renewal of the platinum contacts, I provide a metal platinum holder having the platinum points or contacts thereon, and a spring mounting 20 in which the said platinum holder is removably supported. With this arrangement the platinum holder or portion-bearing platinum contacts is easily inserted and removed, thus facilitating inspection for purposes of 25 cleaning or repairing.

The nature and advantages of my invention, however, will hereinafter more fully appear.

In the accompanying drawings, Figure 1 30 shows a pair of cooperating relays of the character employed, for instance, in the automatic selector and connector switches of an automatic telephone exchange system. Fig. 2 is a perspective view of the relay 35 springs and contacts, the same being organized into a structure which is removable as a unit. Fig. 3 is a perspective of the spring mounting for the platinum holder. Fig. 4 is a perspective of the said removable platinum holder.

As thus illustrated, the relay magnets A can be of any suitable, known or approved construction, and may be provided with suitable armatures a. It will be seen that 45 the magnet mountings a' are bent upwardly to support the said armatures, and are preferably connected together by screws or bolts a'. Between these magnet mountings are clamped the superimposed layers of insulation B and the contact springs operated by the said armatures. The flexible or movable springs C are provided with terminals c. The spring mounting D is provided with a terminal d, and also with inner and outer

clamping or gripping portions d', d² and d³. 55 It will be seen that the faces of these clamping or gripping portions are slightly recessed to receive the flat and preferably pointed end portion e of the platform holder E. A lug or small rounded portion e' on 60 said holder engages the inner edge of the spring portion d³, as shown in Fig. 2, to prevent displacement of the platinum holder. It will also be seen that the said holder E is provided with stops e² for limiting the 65 insertion of same in the spring mounting D. The outer portion e³ of said holder is provided with oppositely projecting platinum points e⁴, adapted to be engaged by the flexible relay springs C. In this way the 70 relay springs and the removable platinum holder and the spring mounting for the latter are all clamped together by the bolts a², and thus organized into a structure which is removable as a unit from the balance of 75 the relay mechanism. Should the said platinum points e⁴ become impaired in any way, the holder E can easily be removed to permit repairing of the said platinum points, or to permit the insertion of a new holder. 80 Thus it is not necessary to take the relay structure apart in order to remove the platinum-bearing member or holder thereof.

It will be understood, of course, that the contacts or anvils e⁴ of the relay can be made 85 of any suitable conducting material.

What I claim as my invention is—

1. A relay provided with a removable and 90 slideable holder having platinum contacts and flexible circuit-closing springs adapted to be pressed into engagement with the said platinum contacts by the energizing of the relay.

2. A relay comprising a removable contact member, a spring mounting from 95 which the said contact member is readily removable, and a movable circuit-closing member adapted to be pressed into engagement with the said contact member by the energizing of the relay.

3. A relay comprising a spring mounting having opposed clamping or recessed gripping portions, a holder removably inserted in said clamping or gripping portions, a contact carried by said holder, and a circuit-closing member adapted to be pressed into engagement with the said contact by the energizing of the relay.

4. In a relay, the combination of a spring 45
mounting, a contact member removably
inserted in said spring mounting, and a
circuit-closing member adapted to be pressed
5 into engagement with the said contact mem-
ber.
5. A relay provided with a group of
switch springs and contacts which are re-
movable therefrom as a unit, including a re-
10 movable contact member and a spring
mounting for the same, and a circuit closing
contact adapted to be pressed into contact
therewith.
6. A relay provided with a slidable holder
15 provided with platinum contacts, and flex-
ible springs disposed at opposite sides of
said holder, adapted to be pressed into en-
gagement with the said platinum contacts
by the energizing of the relay.
- 20 7. A relay comprising a slidable contact
member, a spring mounting from which the
said contact member is readily removable,
and a movable circuit-closing member
adapted to be pressed into engagement with
25 the said contact member by the energizing
of the relay.
8. A relay comprising a spring mounting
having opposed clamping or recessed grip-
ping portions, a holder slidably inserted in
30 said clamping or gripping portions, a con-
tact carried by said holder, and a circuit-
closing member adapted to be pressed into
engagement with the said contact by the
energizing of the relay.
- 35 9. In a relay, the combination of a spring
mounting, a contact member slidably in-
serted in said spring mounting, and a cir-
cuit-closing member adapted to be pressed
40 into engagement with the said contact mem-
ber.
10. A relay provided with a group of
switch springs, contacts which are remov-
able therewith as a unit, including a slidable
- contact member and a spring mounting for
the same.
11. In a relay, a removable contact mem-
ber provided with a lug, and spring means
engaging said lug, whereby the lug and
spring coöperate to removably hold the con-
tact member in place. 50
12. A plurality of electrical circuit-closing
springs, strips of insulation interposed be-
tween the same, means for binding the
superimposed contact springs and strips of
55 insulation together, and a stationary con-
tact member removably applied to a plurality
of said springs and adapted to coöperate
with one or more of the other springs in
closing electrical circuits.
13. In a relay, one or more movable cir-
cuit-controlling springs, a stationary contact
member extending at right-angles to said
spring or springs, so that each crossed the
other, and means whereby said contact mem-
ber is insertible and removable in an endwise 60
direction.
14. In a relay, a spring plate provided
with oppositely-facing spring clamping por-
tions, a contact member inserted between
said oppositely-facing spring portions, and
70 removably held thereby, and means adapted
to engage said contact member to close an
electrical circuit.
15. In a relay, a stationary contact or an-
vil, one or more movable springs for en-
gagement with said contact or anvil, dis-
posed crosswise thereof, and means whereby
75 said contact or anvil is removable indepen-
dently of and without disconnecting said
springs.

Signed by me at Chicago, Cook county,
Illinois, this 24th day of November, 1906.
JOHN ERICKSON.
